FURNITURE MADE OF LAMINATIONS OR SECTIONS

Luther G. Simjian, Riverside, Conn., assignor to
The Reflectone Corporation, Stamford, Conn.,
a corporation of Connecticut

Application October 22, 1949, Serial No. 122,997

5 Claims. (Cl. 155—184)

1

This invention relates to furniture, and more particularly, the economical assembly of an article of furniture through the utilization of a series of individual parts adapted to be brought together to function as a single assembled unit.

In the manufacture of upholstered chairs, stools, hassocks, and the like, considerable expense is involved in the assembly of the component parts and in the upholstering operation. Therefore, upholstered hassocks, as an example, are costly due to the need for considerable skilled labor and the wastage of materials because of the necessity of shaping the upholstering material to the configuration of the hassock.

It is the object of my invention to contribute a hassock, chair, stool or the like, manufactured in such a manner that the upholstering operation is extremely simple and may be performed without highly skilled labor such as is required in the upholstering of conventional hassocks, stools, chairs or the like.

As a feature of my invention whereby the objects thereof are attained, an article of furniture of the class to which my invention relates is formed through the assembly of a series of sectional units. Some or all of these sectional units may be upholstered if desired and the upholstering operation is extremely simple because it is only necessary to upholster one exterior surface of each of the sectional units. Preferably, the sectional units are each in the form of a band or sleeve with the upholstering material applied to the exterior peripheral surfaces thereof. By assembling the series of bands, there is built up a complete article of furniture. Then, to the uppermost band or sectional unit there may be applied the seating portion, thereby completing the chair, stool, hassock, or the like, all as those skilled in the art will fully understand.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

2

Referring now to the drawings, Fig. 1 is a perspective view of a stool manufactured in accordance with the teachings of my invention. Fig. 2 is a perspective view of a stool that is differently shaped. Fig. 3 is a section of the structure of Fig. 1, and is taken along lines 3—3 of Fig. 4. Fig. 4 is a section of Fig. 3 taken along lines 4—4 of Fig. 3. Fig. 5 is an enlarged detailed view of different means for use in assembling the several sectional units of my invention. Fig. 6 is a perspective exploded view showing a further modified form of means to assemble the sectional units forming an article of furniture.

Referring now more particularly to the drawings, and especially Figs. 3 and 4, reference numeral 10 indicates a circular sleeve-like band to the outer peripheral surface of which is applied upholstering material 11, with a padding or the like 12 positioned between the upholstery 11 and the band 10, as is conventional in furniture of the class described. As is probably best seen in Figs. 5 and 6, the upholstery material 11 may be carried over the upper and lower edges of the band 10 and may be secured to those edges as by gluing or by upholstery nails 13.

In the stool of Fig. 1, there are three bands 10, and between these bands, there may be used bands 14 formed of plastic material, or a specially treated decorative wood. Each band 10 and each band 14 is provided with four rectangular clips 15 as best seen in Figs. 3 and 4, these clips being traversed by four rods 16 threaded at their ends for nuts 17. It is the function of the rods 16 and the nuts 17 to bind in superimposed assembled relation the three bands 10 and the two bands 14 of the article of furniture shown in Fig. 3.

Suitably secured to the uppermost band 10 is a seat S, the wood plate bottom of which is designated by reference numeral 20. Bottom 20 is secured to the uppermost band 10 by a series of rectangular clips 21 screwed to the band 10 and to the wood bottom 20. Bottom 20 is then secured to a bearing plate 23 that is rotatably mounted relatively to a frame 24 carried by four legs 25. It is now obvious that through the simple assembly of the series of bands 10, 14, these bands being readily assembled to the seat S, I obtain a completely upholstered article of furniture.

Those skilled in the art will appreciate fully that when upholstering the furniture, it is merely necessary to apply upholstery material in an extremely simple manner to each of the series of bands that is to be upholstered. It is also extremely simple to upholster the seat S. Then by assembling the various parts, I have a fully and

beautifully upholstered article. The upholstering operation does not require skilled labor because almost anyone, with a minimum of skill, can upholster simple circular bands such as bands 10 or the simple seat S. On the other hand, were anyone to upholster the entire article of furniture of Fig. 1 as a single completed unit, it is obvious that considerable skill would be required to drape the material and secure it. Further, it would be impossible to do this without numerous seams and considerable cutting of material.

In Fig. 2 I show an article of furniture in which the bands are rectangular in shape, but the upholstering operation and the assembly of the parts is exactly the same as was disclosed in the invention of Fig. 1. Of course, no legs need be used where the assembly of bands is to be in the form of a hassock. In Fig. 5, I show a modification of my invention wherein the several bands 10 are assembled by a series of bolts 35 extending through aligned bores 36 in each of the bands 10.

In Fig. 6 the bands 10 and 14 have secured to their inner peripheries a series of brackets 40, each of which is bored at 41, with a bore 42 connecting with the bore 41 and threaded for a fastening stud 43. By merely running a rod 44 through the several bores 41 of the brackets 40, and driving the studs home in binding relation to the rod 44, it is possible to assemble the several bands relatively to the rod 44 and relatively to one another. In this way, a unitary article of furniture may be formed as is the case of the modifications of Figs. 3 and 5.

I now claim:

1. In an article of furniture, a series of bands, upholstering material applied to the outer peripheral surfaces of at least some of said bands, and means for holding said bands in juxtaposed assembled relation.

2. In an article of furniture, a series of laminations applied in vertical superimposed relation, and means for holding said laminations assembled in said vertical superimposed relation with their exterior peripheral surfaces forming a composite exterior surface for said article of furniture.

3. In an article of furniture, a series of laminations applied in vertical superimposed relation, and means for holding said laminations assembled in said vertical superimposed relation with their exterior peripheral surfaces forming a composite exterior surface for said article of furniture, at least some of said laminations being each in the form of a band whose exterior peripheral surface is upholstered.

4. In an article of furniture, a series of laminations, upholstering material applied to each of the outer peripheral surfaces of at least some of said laminations, and means for holding said bands in assembled juxtaposed relation with the outer peripheral surfaces of said laminations forming the composite exterior surface of said article of furniture.

5. In an article of furniture, a series of laminations applied in vertical superimposed relation, means for holding said laminations assembled in said vertical superimposed relation with their exterior peripheral surfaces forming a composite exterior surface for said article of furniture, and a seat applied to the uppermost of said laminations.

LUTHER G. SIMJIAN.
